CURTAIN AND DRAPERY PILOT OR GUIDE

Joseph Elliott, Richmond Hill, N. Y.

Application September 30, 1932, Serial No. 635,475

4 Claims. (Cl. 223—38)

This invention relates generally to devices to be employed in the hanging of curtains and similar draperies and is more particularly directed to a means for facilitating the application of curtains or draperies to their supporting rods, as a so-called pilot, guide or threadder.

As is well known, window or other curtains are customarily suspended from metal rods or wood poles, the rod or pole being inserted within a hem or fold formed at one end of the curtain. Those suspension devices most commonly employed are metallic rods of a channel cross-section, composed of two sections, each embodying a straight portion terminating in a curved end, apertured or otherwise adapted to engage a supporting bracket or the like, fixed to the window or door frame, or other surface with which the curtain or drapery is to be associated. The straight portions of the two sections are formed for telescopic engagement for assembly and disassembly and to render the rod extensible or adjustable to accommodate it to curtains and supporting surfaces of different widths.

In applying a curtain to a rod, the two sections are disassembled and one thereof is threaded through the curtain hem with the straight end of the rod section forming the entering edge, or, alternatively, the rod section may be held stationary and the curtain drawn thereover, the curtain being gathered upon the rod section which is then telescoped into its mate, after which the curtain may be expanded in the desired draping arrangement across the now complete or assembled rod. However, either of these prescribed methods of application is extremely difficult to practice with any degree of celerity and without damage to the curtain, because of the fact that the end of the straight portion of each rod section is substantially sharp, usually embodying rough edges or burrs which are a product of the stamping operation, whereby the rods are formed, upon which the curtain material impinges; in many instances, resulting in tears or damaged areas in the hem and adjacent parts of the curtain, that render it unfit for service.

Even with the exercise of great care, the prevention of tears or breaks in the material, during the curtain threading operation is most difficult, the difficulties being multiplied with a concomitant increase in the likelihood of damage to the curtain, where it is constituted of a material of a soft or sheer texture, as in many of the expensive draperies.

Therefore, the general object of this invention is to provide a method and means of applying

curtains and similar draperies to sectional metallic rods, whereby the work will be greatly facilitated and, at the same time, the material of which the curtain is composed will be safeguarded against injury or damage by the rod section, in 60 the association of the curtain therewith.

More specifically, it is the object of this invention to provide a pilot or guide for use in locating or arranging curtains and similarly hemmed draperies upon a metallic hanging rod, or section thereof, which is of a simple, economical and efficient design and is susceptible of application to rods, or their sections, of different sizes, so as to impart to my invention a wide range of utility.

Another object of my invention is the provision of a pilot or guide, as hereinbefore set forth, which may be readily applied to and detached from the curtain rod, or rod-section with which it is to be used and will function in conjunction with such rod, or section, to insure the free passage or movement of the rod within the curtain hem, in which it is insertable, irrespective of the softness or clinging characteristics of the curtain material or of a condition of the rod material at its hem-entering end which, in the absence of such pilot, would tend to impair the progression of the curtain along the rod or rod-section, as in the conventional threading operation.

My invention further contemplates a so-called pilot or curtain threading device, whereby a curtain may be expeditiously applied to a curtain rod, or a rod-section, which will enclose or house the end of the rod or rod-section to which it is applied and operate to guide the rod through the curtain hem within which it is locatable, my said device including yielding means for detachably retaining it in functioning association with the rod, or rod-section, to which it is applied 95 for the performance of the intended work.

Other objects and advantages flowing from the practicing of my invention will doubtless present themselves as the description proceeds and I would have it clearly understood that I 100 reserve unto myself, all rights to the full range of equivalents, both in structure and in use, to which I may be entitled under my invention in its broadest aspect.

For the purposes of the present disclosure, I 105 have elected to illustrate and describe a preferred embodiment of my invention. However, my invention may take other forms, without departing from the spirit and scope thereof, as defined by the appended claims.

In the drawing:

Figure 1 is a view in perspective, showing the application of my invention to a curtain rod-section and the mode in which it functions to 5 pilot the section through the curtain hem.

Figure 2 is an enlarged longitudinal section of the pilot or threader illustrated in Figure 1.

Figure 3 is a top or front plan view of my improved pilot or threader, with a fragment of 10 a curtain rod-section seated therein, portions of each being shown in dotted lines to indicate their relative positions in assembled relation.

Figure 4 is a transverse section on the line 4—4 of Figure 3, and

Figures 5 and 6 are respectively plan and side elevations of the yieldable retaining means of my 15 device.

Referring now to the drawing in detail, in which like characters of reference are employed 20 to indicate similar parts in the several views, a fragment of a curtain or piece of drapery is shown at 7, which embodies the usual hem 8 formed by folding the fabric upon itself and stitching the fold along the line 8a.

While my invention, as will be evident, may 25 be applied to various types of curtain rods, annular or of other cross-section, and to rods of different widths or diameter, I have herein shown it as it may be utilized in conjunction with that 30 type of curtain rod which is most commonly used, one which comprises two like sections having a channel cross-section, one of the sections telescoping within the other. A fragment of a section of such a rod is indicated at 9, it being noted that the side-forming flanges there- 35 of are curved inwardly, as at 10, the edges thereof being substantially parallel through the length of the rod. As previously pointed out, each rod section embodies a straight portion merging into 40 a curved attaching portion, whereby the rod, when assembled, may be mounted on a suitable support.

The straight portion of the rod, at the end 45 remote from the curved attaching part, is sheared off in the stamping operation, by which the rod-section is formed, to present a substantially straight edge, or one which may project outwardly of the terminal portions of the flanges abutting thereon, and have a curved or somewhat angular contour. Usually, this projecting surface is somewhat irregular in outline, as shown 50 in dotted line, indicated at 9a in Figure 3 of the drawing, due to the relatively thin stock or metal from which the rod is formed and the shearing action of the cutting tool; the fact that this end of the curtain rod section is wholly 55 concealed by the curtain suspended therefrom when in use, causing the rod manufacturers to disregard any lack of uniformity of contour or other irregularities that may occur therein, or 60 in the side flanges, which, similarly to the web are usually more or less rough and frequently burred. As this end 9a must function as the entering portion of the rod section, when the curtain is to be gathered or threaded thereupon, it will be obvious that any sharp surfaces, or 65 burrs or other inequalities in the metal of the web or flanges will be productive of difficulties in the threading operation. The curtain material, usually is of a soft texture, and, since there 70 is no practical method of distending the hem or fold 8 throughout its length, that the rod section may pass therethrough without contacting with the hem material, the threading operation must be performed very slowly, the curtain being moved 75 over the entering end of the rod section a little

at a time and simultaneously drawn or stretched laterally and vertically, relatively thereto, in the effort to keep it out of contact with the sharp edges of the rod end, so as to avert tearing or breaking of the texture of the curtain material. Notwithstanding the most painstaking effort, however, the curtain threading operation is usually productive of tears or abrasions in the curtain material, as it catches upon some sharp projection in a flange or along the edge of the web of the rod section.

My pilot or threader, as will be clearly seen from Figure 1 of the drawing, is adapted to be applied directly to the afore-described entering end of the curtain rod section and comprises a head in the form of a receptacle 11 which is suitably dimensioned to wholly enclose the web and portions of the flanges 10 adjacent such end, it being apparent that the internal profile of the head conforms substantially to the external contour of the rod section in the zone of contact, the periphery of the head therebeyond being of an appropriate curvature to effect the dilation of the curtain hem, so that the pilot and rod may follow freely therethrough.

As will be observed, one surface of the receptacle 11 is extended to constitute a plate 12, the sides 13 of which preferably converge toward the extremity 14 thereof, this plate, similarly to the head, being formed from sheet metal and being substantially rigid, so as to lie flat against the outer surface of the web 9, when the head is located upon the end of the rod section, as hereinafter described.

Preferably fixed at one end to the inner wall of the head or receptacle 11, as by welding, riveting or the like, I provide a spring 15 formed from so-called flat stock, which normally abuts upon the aforesaid plate 12, the free end of said spring being rolled or turned upwardly, as at 16. Intermediate of its ends, the spring may be distorted or bent, as at 17, to increase the pressure that may be exerted thereby upon the plate 12, throughout the area thereof with which the spring remains in contact.

From the foregoing, it will be manifest that in the use of my pilot, it is applied to the end of the rod section which is to be located within the curtain hem by alining the end 4 of the plate 12 with the outer surface of the web 9 of the rod section and urging the pilot longitudinally of the rod so that the spring 15 will enter upon the inner face of the web and traverse the same until the head encases the web and flange portions to provide a protective covering therefor, as heretofore set forth, it being evident that the pressure exerted by the spring 15 counter to the plate 12 will produce sufficient clamping effort to retain the pilot in functioning position. With the pilot applied to the rod end, as described, the rod section may be readily inserted within the curtain hem, either by drawing the curtain thereover, or by moving the rod section through the hem, the smooth rounded surface of the head of the pilot readily effecting the dilation of the hem, even in those instances where the material of which the curtain is made is of a soft clinging texture. As the gathering of the curtain upon the rod section is completed, the pilot may be removed or detached from its functioning position, simply by grasping the head and withdrawing it longitudinally of the rod, the rod section being then telescopically engaged with its mate and the curtain draped upon the completed rod.

While the spring 15 may take other forms and

be otherwise affixed to the head, than heretofore described, I prefer to utilize a strip of material long enough to conform a portion thereof to the inner wall of the receptacle to impinge upon the parallel walls and the curved connecting end wall, the spring within the receptacle thus taking the shape shown in elevation in Figure 6, and generally indicated by the reference character 15a. In order to afford sufficient clearance for the passage of the receptacle-contained portion of the spring between the rod flanges, as the rod is urged to its limit of movement within the head, the sides of this portion of the spring may be undercut as shown at 15b in Figure 5, the major part of the spring being of a uniform width that will afford a sufficient area for the efficient performance of its intended function.

While the head and the plate 12, as herein shown are integral or a unitary structure, the head may be separately formed and welded or otherwise affixed to the plate or a similarly functioning shank element, or the plate and one surface of the head may be struck from a single blank of material, as spring steel to which a formation to constitute the head in conjunction with a portion of said blank may be joined. In such a construction, if desired, in lieu of the independent spring clamping element, a tongue may be formed by suitable incisions in the spring steel plate and suitably set to function in co-operation with the plate to exert the requisite clamping effort upon the web of the rod when interposed between said plate and its integrally formed tongue. Obviously, such modified forms of my invention and other embodiments thereof will come within the purview of the following claims.

I claim:

1. A device for guiding curtains and similar draperies onto a supporting rod, comprising a rigid plate, a receptacle associated in fixed relationship thereto, said receptacle being adapted to receive the end of the curtain or drapery supporting rod and enclose the same, the said plate contacting with an external surface of the rod inwardly of its end and yieldable means fixed within said receptacle and superposed upon said plate, said latter means engaging the surface of said rod opposite to that with which said plate contacts, coincidentally with the entering of the end of the rod into said receptacle.

2. A device adapted to be associated with the end of a curtain supporting rod, to facilitate the threading of a curtain or the like upon said rod, said device embodying a receptacle formed to

embrace the end of the rod and providing a head having a curved peripheral contour constituting a virtual continuation of said rod, a rigid element forming an extension of a part of the wall of said receptacle and a flat spring adapted to yieldingly engage a surface of a flat portion of the rod opposite to that upon which said rigid element is adapted to bear in flat contact, to clamp said device in functioning position upon said rod by a single operation, said device serving to dilate the rod-receiving hem of the curtain or the like and pilot the rod therethrough.

3. The combination with a curtain rod, of a device for piloting the end of said rod through the rod-receiving hem of the curtain, said device embodying a plate-like shank, a head supported from said shank and formed to receive and embrace the end of the rod, said head having a cross-section conforming substantially to that of the rod, with an external profile presenting an entering surface curved in all directions, and a spring disposed upon said shank and connected in said head adapted to frictionally engage a surface of the rod opposite to that upon which said shank is locatable to retain said device in functioning position upon said rod, said spring and said shank clampingly engaging the rod body simultaneously with the entry of the end of the rod into said head.

4. A pilot adapted to be detachably connected to the end of a curtain supporting rod of a shallow channel cross-section to facilitate the location of said rod within the curtain hem, said pilot embodying a head shaped to form a receptacle to receive and enclose the web and flanges of said rod adjacent one end thereof, the internal profile of said head conforming substantially to the external contour of the rod, a plate forming a continuation of a part of the surface of said head adapted to lie in flat contact with the external surface of the web of said rod contiguous to the enclosed end thereof and a substantially flat spring joined to said head at one end and superposed upon said plate, said spring being shaped to enter between the flanges of the rod to engage the inner face of the web thereof, and cooperate with said plate to retain said head in position upon said rod, coincidentally with the location of the rod end within said receptacle the peripheral contour of the entering portion of said head serving to effect the dilation of the curtain hem to admit of the pilot and the rod passing freely therethrough.
